UNITED STATES PATENT OFFICE

137,999

DESIGN FOR A SKATE SEAT

Richard J. Daly, New York, N. Y.

Application October 15, 1943, Serial No. 111,366

Term of patent 7 years

(Cl. D34—14)

To all whom it may concern:

Be it known that I, Richard J. Daly, a citizen of the United States of America, residing at New York, county of New York, and State of New York, have invented a new, original, and ornamental Design for a Skate Seat, of which the following is a specification, reference being had to the accompanying drawing, forming a part thereof, wherein:

I claim:

The ornamental design for a skate seat, as shown.

RICHARD J. DALY.
